The lubricating shoe 18 is provided with a notch 24 at its outer end formed so as to conform to the contour of the flange 25 of the driving wheel 26. The notch 24 is formed so as to fit snugly around the flange 25 and in this manner prevent the lubricant from spreading over the tread 27 of the wheel 26. A clamp 28 fits around the shoe 18 as is illustrated in Figs. 1 and 6, and this clamp comprises a pair of sections having their upwardly extending ears 29 secured together by means of a transversely extending bolt 30. Between the lower parallel ends of the clamp 28 are secured a plurality of weighted plates 31 for the purpose of constituting means for preventing the lubricating shoe 18 from jumping out of engagement with the flange 25 of the wheel 26. A chain 32 is secured to the bolt 31 as is illustrated in Fig. 6, and this chain passes around the T-joint 15 as illustrated in Fig. 3 and constitutes a support for limiting the downward swing of the lubricating shoe 18.

By carefully considering Fig. 5 it will be seen that the pipe 17 extends into a passageway 33, which passageway communicates with an off-set passageway 34, whereby the lubricant may be forced down into engagement with the inner face of the flange 25 of the wheel 26, and thereby deposit lubricant at the desired point upon the flange 25.

The reservoirs 3 which are placed upon either side of the locomotive are connected 35 by means of a connecting pipe 35 to which connecting pipe is secured the supply pipe 10 above described.

The operation of the device is as follows:—The lubricant is placed in the compartment 5 and the valve 21 is opened. The lubricant will then pass out through the pipe 20 through the T-joint 15 and down through the lubricating shoe 18 to the flange 25 of the wheel 26. In order that the lubricant may not get gummy or clogged especially in cold weather it has been found preferable to pass a supply of exhaust steam adjacent the lubricating compartment 5 as is provided in the structure as illustrated in 50 Fig. 3. The exhaust steam is fed into the steam compartment 6, thereby efficiently heating the lubricant within the compartment 5 as the same passes through the pipe 20 so as to insure the free feed of the lubricant material. If, however, in extremely

cold weather it is desired to take additional precautions for insuring the liquefying of the lubricant the valve 13 may be opened and the exhaust steam may pass down through the pipe 12 and also pipe 14 and assist in forcing the lubricant and also liquefying the lubricant as the same passes through the lubricating shoe 18. Under ordinary circumstances when it is not necessary to employ the steam to assist in forcing the lubricant down through the shoe 18, the exhaust steam will pass out through the pipe 23 and be discharged from the casing 6.

Having thus described the invention what is claimed as new is:—

1. A lubricator of the class described comprising a reservoir, said reservoir provided with a lubricating compartment, a steam compartment, means for feeding steam to said steam compartment, a lubricant supply pipe communicating with said lubricating compartment and passing through said steam compartment whereby lubricant may be heated while passing through said steam compartment, means for controlling the flow of lubricant from said lubricating compartment, a yieldably supported lubricating shoe communicating with said lubricating compartment, steam discharge means communicating with said steam compartment, and means forming a communication between said steam compartment and said lubricating shoe for facilitating the forcing of lubricant through said lubricating shoe.

2. A lubricator of the class described comprising a reservoir, means for heating said reservoir, a lubricant supply pipe, a lubricating shoe suspended from said lubricating supply pipe, a clamp carried by said lubricating shoe, said clamp provided with a pair of parallel depending members, weights carried by said parallel depending members, said weights adapted to normally hold said lubricator against upward movement, and a supporting chain secured to said lubricating supply pipe and engaging said clamp for adjustably and yieldably supporting said lubricating shoe.

In testimony whereof I hereunto affix my signature in presence of two witnesses.

ANTON ALBERTSON.
